UNITED STATES PATENT OFFICE

95,389

DESIGN FOR A COMBINED DIAL TELEPHONE HOLDER AND ILLUMINATOR

Dewey E. Towner, Kansas City, Mo.

Application January 21, 1935, Serial No. 54,968

Term of patent 7 years

To all whom it may concern:

Be it known that I, Dewey E. Towner, a citizen of the United States, residing at Kansas City, in the county of Jackson and State of Missouri, have invented a new, original, and ornamental Design for a Combined Dial Telephone Holder and Illuminator, of which the following is a specification, reference being had to the accompanying drawing, forming a part thereof.

Figure 1 is a perspective view of the combined dial telephone holder and illuminator.

Fig. 2 is a plan view of the same.

Fig. 3 is a rear elevation, and,

Fig. 4 is a side elevation.

I claim:

The ornamental design for a combined dial telephone holder and illuminator as shown.

DEWEY E. TOWNER.
